UNITED STATES PATENT OFFICE.

CHARLES B. PENDLETON, OF DENVER, COLORADO.

AUTOMATIC FLUID-PRESSURE DISPLACEMENT-PUMP.

1,368,528.

Specification of Letters Patent. Patented Feb. 15, 1921.

Application filed November 11, 1919, Serial No. 337,146. Renewed July 17, 1920. Serial No. 397,154.

To all whom it may concern:

Be it known that I, CHARLES B. PENDLETON, a citizen of the United States, residing at the city and county of Denver and State 5 of Colorado, have invented certain new and useful Improvements in Automatic Fluid-Pressure Displacement-Pumps; and I do hereby declare the following to a full, clear, and exact description of the invention, such 10 as will enable others skilled in the art to which it appertains to make and use the same.

This invention relates to automatic fluid pressure liquid displacement pumps, and 15 for the purpose of specifying one sphere of its usefulness it may be said to have been primarily devised for the pumping of oil wells. It is desirable to state at the outset, however, that the improvements are also 20 adapted for installation in other analogous relations and for the pumping of other liquids than oils, as occasions might arise.

Production from the wells of an oil field is to an extent dependent upon the drainage 25 conditions of the oil bearing strata and the more or less seeping or retarded flow of the oil into the well casing, so that regardless of the quantitative volume of the supply source the output is largely governed by 30 said drainage conditions and the varying subterranean pressures. The rate of flow is, therefore, naturally slowed down as the underground pressure is partly relieved, which will of course follow in due time after the 35 well has been brought in. Also the head of oil falls in the casing, and pumping operations, becoming necessary, must be carried on periodically or at suitable intervals because the pumped discharge is not immediately 40 compensated for by a corresponding inflow of oil into the casing. Hence it follows that the frequency of the pumping operations becomes an important factor, especially owing to the productive limitations of 45 a given field and the number of rival wells exhausting the supply thereof, and for a maximum recovery of oil these pumping operations should be as nearly continuous as may be, or at least started up immediately 50 as each pumped out casing is again filled to the desired pumping level.

However, with the general types of pump riggings heretofore employed, anything like an approach to continuous pumping opera-

tions is not practically feasible, as will be 55 well understood by those engaged in the industry, and as a matter of fact many well casings fill up to the requisite pumping levels long before others do, thus being left 60 idle and unproductive in that state for an indefinite period, whereas the pumps are only operated about three or four times a day, and then in a collectively balanced group as a rule.

Also, these pump riggings are constantly 65 getting out of order, perhaps owing to their numerous parts, and they are of a more or less complex structure, entailing considerable expense from the viewpoints of manufacture, installation, repair and operation. 70

One of the main objects of the present invention, therefore, is to overcome all of these objectionable features, and others which will not be enlarged upon, not only as to decreased costs of manufacture and installation 75 but also as to prolonged durability and maximum efficiency and economy in operation. Other objects and advantages will be so clearly apparent, as incidental to the following disclosure, that further initial reference thereto would serve no useful purpose 80 and would only be undesirable surplusage.

In the accomplishment of the desired ends, the instant invention particularly embodies a novelly combined arrangement of a paired 85 set of valvular parts with co-operating and co-acting elements which are so operatively housed within a suitably walled liquid displacement chamber as to function automatically, in the positive control of pumping operations, both with reference to the opening 90 of a displacing pressure fluid line, functioning as hereinafter referred to, immediately upon a predetermined level having been reached by the liquid supply in the well casing, for starting up and continuing the pumping force until the volume of liquid then in the displacement chamber has been discharged, and also as to the shutting off 95 of the pumping force while opening communication between the well casing and displacement chamber for refilling the latter. Thus the periodical pumping operations are automatically conducted, without any particular attention whatsoever on the part of 100 an operative, assuming that the pressure fluid line is maintained on, and it is obvious 105 that such operations may be continued

throughout the night, if desired, as well as during the day.

- It may be further said that the pump elements are so disposed in combined relation 5 as to be adapted to be lowered into and withdrawn from a well casing as an assembled bodily whole, the lower portion of the said displacement chamber being both in controlled communication at its bottom zone 10 with the well casing and also with a liquid discharge conduit, at a position a little higher up, by virtue of the dual functioning of one set of said valvular elements generically termed of the "foot-valve," while 15 the upper zone of the displacement chamber provides for controlled communication with the liquid displacing pressure fluid line, by way of a check valve and the other set of said valvular elements, which latter may be 20 conveniently termed the "head valve" as briefly distinguished from said foot valve, and this head valve also controls a pressure fluid conduit leading from said pressure fluid line to the interior of said foot valve's 25 casing, the functioning of all of which elements will more specifically appear later on.

With these prefacing remarks, and for a clearer understanding of the gist of the invention as succinctly set forth in the appended claims, reference will now be had to the accompanying drawings, illustrating a practical embodiment of the improvements, in which drawings—

Figure 1 is a longitudinal sectional view 35 with some of the parts broken away, taken substantially in the plane of the line 1 of Figs. 4 to 7, and illustrating an application of the improvements within the lower end of a well casing, the valves shown being disposed in one of their extreme positions; Fig. 2 is a longitudinal sectional view taken at right angles to Fig. 1 and substantially in the plane of the line 2 of Figs. 4 and 5 and the line 3 of Figs. 6 and 7, in which view 40 the check valve is also shown and in its shut-off position; Fig. 3 is a longitudinal sectional view, analogous to Fig. 2 but with all of the valves moved to their extreme positions just the reverse of those shown in 45 Figs. 1 and 2; Figs. 4, 5, 6 and 7 are transverse sectional views respectively taken substantially in the planes of the lines 4, 5, 6 and 7 of Fig. 1, the well casing being omitted; and Fig. 8 is a fragmentary sectional 50 view, analogous to Fig. 1 but showing the head valve in an intermediate position, as it is being moved downwardly, and more especially illustrating a small float valve, by way of a minor modified arrangement, for 55 controlling a relief by-pass extending from the upper zone of the displacement chamber to the liquid discharge conduit leading to the atmosphere.

10 represents the lower end of a well casing and 11 designates a vessel, preferably

of tubular form as shown, which is adapted to be suitably supported within the well casing as well as being adapted to receive the liquid to be pumped, in measured charges as it were, and also a pressure 70 charge, functioning as fluid piston means for forcing the contained liquid through a discharge conduit leading out of the well. For convenience, this vessel may be properly termed the displacement chamber, and 75 while it may be made of different capacities we will assume that it is four feet in length and four inches in diameter; as an approximate idea of its dimensions.

The ends of this tube 11 are suitably 80 threaded, preferably internally, for the proper attachment of a bottom and a top closing plug, the bottom plug 12 having a longitudinal bore 13 which may be axially disposed, or offset from the center as shown, 85 and the top plug provides a suitably bored and chambered closure, for various purposes, encompassed by a cylindrical containing wall 14.

15 designates a tubular shank of a foot 90 valve casing, the lower end of which is slightly reduced to pass snugly through the bore 13 and a threaded to receive a jam-nut 16 adapted to abut an externally formed boss on the bottom of the plug 12, which arrangement permits of the foot valve casing 95 being rigidly supported in place.

Oil inlet means are provided for the tubular shank portion 15, which may consist of a series of orifices or annularly disposed 100 ports 17, and the upper end of this shank portion merges into an open ended hollow head 18, providing an enlarged operating chamber 19 for the reception of a cup-shaped piston member 20 of the reciprocating 105 foot valve proper.

The piston member 20 is formed with a depending stem 21, preferably hollowed out for lightness, functioning as a slide valve element controlling the ports 17, and the 110 said piston member is also formed with an upwardly projecting central stud 22, rounded off to serve as a stoppering or plug valve element, and which is dimensioned to leave a substantial annular pressure head face 23 at the top of the piston member.

The hollow head 18 is surmounted by a ported capping head, adapted to be threaded thereon and comprising an upper and a lower 120 thickened disk section, respectively designated at 24 and 25, which are joined in spaced relation by diametrically opposite vertical posts or circumferential wall sections 26, providing a ported opening or transverse 125 passageway therebetween, as indicated at 27.

Both the upper and the lower disk sections 24 and 25 are centrally apertured, as at 28 and 29, for suitably receiving the reciprocal rounded stud 22, and they are likewise 130

provided with smaller apertures 31 and 30 disposed in alinement, the aperture 30 serving as a pressure fluid inlet opening into the top of the chamber 19 above the pressure head face 23 of the piston member 20.

5 The top closing plug, for the displacement chamber, has an axially offset longitudinal bore 32 therethrough, the external end of which is fitted with a discharge pipe 10 33 leading to the top of the well casing, while the internal end thereof is connected by a pipe fitting 34 with the upper end of the aperture 28 through the capping head disk 24 which is threaded to receive it.

15 The said top closing plug is also chambered, as before referred to, providing an enlarged pressure fluid compartment 35, and its bottom confining wall is apertured, as at 36, to provide for a suitable communicating 20 connection with a pressure fluid conduit 37 leading to the inlet aperture 30 of the piston member chamber 19, the pipe 37 passing through the aperture 31 of the ported capping head.

25 Analogously, the compartment 35 is also tapped by an aperture 38 to provide for a pressure fluid communicating connection with an elongated valve pot 39 depending within the aforesaid displacement chamber 30 and having a series of ports 40 opening into the upper zone thereof, which ports are controlled by a suitably mounted retractile piston valve element 41. This is shown to function somewhat after the fashion of a 35 pop valve arrangement associated with a coil spring 42, but it is obvious that the same end could be accomplished by equivalent means—for instance by the employment of a U-bent pipe, instead of the valve pot 40 39, with its free end upturned and providing a valve seat, also functioning as an outlet port, upon which a gravitating check valve is suitably mounted and retained so as to be opened by the pressure fluid and 45 closed, by its own weight, when the pressure fluid is shut off.

The top closing plug is further provided with an elongated vertical valve bore, the upper section 43 of which is of restricted 50 diameter and merges at its lower end into an enlarged valve head chamber 44, opening into the aforesaid displacement chamber but maintained closed directly thereto as will later appear.

55 A pressure fluid inlet port for the compartment 35 is shown at 46, being in controlled communication with a pressure fluid line 48 by way of an elongated port 47, opening into said bore 43 at a position 60 posed to the port 46.

49 indicates a port opening between the bore 32 and the valve head chamber 44, and 50 is a co-operating port opening between said valve head chamber and the upper end 65 of the aforesaid displacement chamber by

way of a tapping orifice 51, the arrangement providing for a by-pass channel, through said valve head chamber, from the displacement chamber to the pumped liquid discharge pipe, as clearly seen from Figs. 1, 5 70 and 8; and it is desirable that the port 50 opens to the chamber 44 at a position slightly below that of the port 49.

52 designates a stem member forming an upper continuation of the head 54 of a valvular element, the stem 52 having an annular groove 53, intermediate of its length, adapted to be brought into and out of registration with the port openings 46 and 47, it being understood that the parts 52 and 54 80 are snugly fitted to reciprocate within their respective bore housings 43 and 44 to function in the manner of a slide valve, for respectively controlling communication between the port openings 46—47 and 49—50, 85 and in fact they constitute the head valve proper of the improved pump.

55 simply indicates a cross-bar disposed within the ton of the displacement chamber underneath the valve head bore 44, which 90 cross-bar may be suitably supported at its ends by the pipe 37 and the dash pot 39, its function being to limit the downward movement of the head valve to prevent the latter from entirely dropping out of its housing 95 bores; but it is obvious that any other means may be employed for this purpose.

56 designates a float suspended from the valve head 54 by a shank or stem passing through an aperture in the cross-bar 55, and in the slightly modified arrangement, illustrated at Fig. 8, there is also shown any suitably mounted float valve 57 associated with the tapping orifice 51, forming a part of the by-pass channel before mentioned; 100 but these float elements are only for minor details, either one or both of which may be employed or dispensed with, largely dependent upon expediency under some conditions, and their specific functioning will 105 later appear in the particular statement of operations.

From Figs. 1, 6 and 7 it appears that the whole foot valve arrangement is centrally offset in the displacement chamber, but it 115 is obvious that the bore 13 of the bottom plug 12 may be centrally located to axially center the foot valve if desired, and which would be compensated for by making a slight offsetting bend in both of the pipe fittings 34 and 37. This is really immaterial in point of functioning, although it might be desirable in commercial manufacture so as to permit of the use of a standardized 120 centrally bored plug.

125

Operations.

When the head of oil in the well casing is below the operative level of the head valve, it is obvious that pumping action will 130

temporarily cease as the displacement chamber may only be filled to that level also under such conditions. However, if the oil has risen in the well casing substantially 5 above the head valve, and assuming that the parts are positioned as in Figs. 1 and 2, then it follows that:—

The head valve has been moved to its extreme lowermost position, the pressure fluid 10 receiving chamber 35 being closed to its supply line 48, by the stem 52 covering the port openings 46—47, and the by-pass channel 49—44—50—51 being open between the upper end of the displacement chamber and 15 the bore 32, while the check valve 41 will be positioned above its complementary ports 40 thus closing communication, through the aperture 38, between the displacement chamber and the pressure fluid receiving chamber 20 35. Reversely, the foot valve is elevated to its extreme uppermost position, with the stud plug 22 thereof stoppering the aperture 28, in which is fitted the inner end of the discharge pipe connection 34, and with the 25 depending stem 21 of the piston member uncovering the ports 17 through the hollow shank 15 of the foot valve casing. It is therefore apparent that communication will be closed between the lower end of the 30 displacement chamber and the outlet conduit pipe 34, by means of the stud plug 22, while it is open between the well casing and the displacement chamber by way of the lower end of the hollow shank 15 and un- 35 covered ports 17. Accordingly the oil will flow freely into the displacement chamber from the well casing, under whatever head pressure it may have in the latter, and during this flow a vent, for any cushioning air 40 above the volume of oil in the displacement chamber, is provided by the by-pass channel leading through the chamber 44 to the bore 32.

As the rising oil level approximates the 45 top of the displacement chamber its pressure alone, directly upon the bottom face of the enlarged valve head 54, will ordinarily suffice to properly elevate the head valve 52—54 as an entirety. This would be especially true perhaps where the head of oil stood high up in the well casing and would correspondingly increase the pressure within the displacement chamber. Under such high pressure conditions, however, oil might 50 be spurted up through the orifice 51 and into the chamber 44 above the valve head 54, which to an extent might impede the upward movement of the head valve after the fashion of a dash pot or liquid cushioning 55 means, and even by the admission of a choking foreign substance contained in the oil. On the other hand, should the oil rise slowly 60 in the displacement chamber, under a low pressure, the chance of such conditions arising would doubtless be augmented, because 65

there would be no accelerated impulse in the upward actuation of the head valve which there would be in a more or less degree under a high pressure, and the oil would probably run up into the chamber 70 44 before the head valve closed the port 50, if indeed under an exceedingly low pressure the head valve was raised at all. At any event it is not desirable that oil from the displacement chamber should actually 75 get into the chamber 44 at all, if only because it would likely suspend grit which would tend to cut or abrade the smoothly finished surfaces of the valve head and its bore. 80

To provide for possible low pressure conditions, therefore, it would seem to be advisable to independently control the by-pass venting channel, unless the upward actuation of the head valve was made more positive, and suitable means are illustrated in Fig. 8 by a conventionally shown float valve 57 coöperating with the orifice 51 as a valve seat therefor, whereby the small float valve would close that orifice before the oil itself 90 could reach the latter. Also, this vent being thus closed the upward pressure on the valve head 54 would be augmented to insure its proper functioning. It is obvious though that any other equivalent means 95 might be employed in lieu of the actual float valve as shown.

Even under high pressure conditions, where the head valve is actuated upwardly solely by pressure thereon, this float valve 100 arrangement might be of considerable advantage for the reasons just stated and also as before stated with reference to the possible spouting of oil up into the chamber 44 above the enlarged valve head 54. 105

On the other hand, this independent control of the by-pass channel is not always strictly essential, as for instance where the head valve is provided with a rigidly suspended float, as indicated at 56 in Figs. 1 to 3, for by this arrangement the head valve would be started upwardly when the oil level rose above the lowest position of its float, whereupon the valve head 54 would first close the port 50 and subsequently the port 49, so that the oil would never reach the orifice 51, the downward displacement of the oil volume being started immediately upon the head valve completing its upward stroke, as will shortly appear. 110 115 120

Viewed as a whole, however, and considering variations in the head of oil in the well casing which will cause a higher or lower pressure upwardly in the displacement chamber, it may be desirable to equip 125 the pump with both the head valve float 56 and the auxiliary floated valve 57, or their equivalents, although it will be understood that either one or both of them may be dispensed with without very greatly in- 130

terferring with the satisfactory operation of the pump.

The displacement chamber having been filled with liquid from the well casing and 5 the head valve elevated to its uppermost position as shown in Fig. 3, the relief orifice 45 serving as a vent into the chamber 35 for any cushioning air above the stem 52, then the annular groove 53 of the stem 52 10 will have been brought into registration with the port openings 46-47. The operating pressure fluid, from its supply line 48, will thus fill up the receiving chamber 35 and passing down the pipe 37 will enter the 15 foot valve's chamber 19 above the pressure face 23 of the piston member 20.

Even though the pressure from the head of oil in the well casing is greater than that of the operating fluid, which is very frequently the case, the difference will be compensated for by the proportionate area of 20 the pressure face 23 of the piston member, so that the foot valve will be immediately actuated downwardly and the lower end of 25 the stem 21 will close the ports 17 slightly in advance of the stud plug 22 unstopping the aperture 28 or the lower end of the liquid discharge pipe connection 34.

The pressure from the well casing being 30 thus relieved, the check valve 41 will then be forced downwardly, by the operating pressure fluid from the receiving chamber 35, to uncover the ports 40, whereupon said pressure fluid entering the upper end of the displacement chamber, through said ports 35 40, will displace its contained liquid and force the same through the transverse passageway 27, of the foot valve's capping head, and thence up through the aperture 40 28, pipe connection 34, bore 32 and pipe 33 to the final discharge outlet exteriorly of the well.

When the oil level in the displacement chamber falls below the ported opening 27 45 the pressure fluid itself will then pass there-through and up the discharge conduit, behind the column of oil being discharged through the latter. During all of this time the pressure, through the pipe 37, on the 50 face 23 of the piston member 20, perhaps supplemented by the internal pressure on the top face of the stud plug 22, will hold the foot valve down in its lowermost position; but as soon as any substantial relief 55 is afforded for the back pressure of the column of oil, as will be the case when the discharge conduit is directly opened to the atmosphere, owing to the substantial expulsion of its column of oil, it will be obvious 60 that the pressure within the displacement chamber will also be commensurately relieved, and there being no buoyant support for the head valve it will gravitate again to its lowermost position, its action being made 65 more positive by the admission of the pres-

sure fluid from the chamber 35, through the relief orifice 45, into the valve bore 43 above the stem 52.

With the operating pressure fluid thus cut off again, it will be evident that the foot 70 valve will in turn be reelevated to its uppermost position by the pressure of the head of oil in the well casing, and also the check valve 41 will be retracted to close communication, between the displacement chamber 75 and the pressure fluid receiving chamber 35, through the tapping aperture 38, while communication between the upper end of the displacement chamber and the bore 32 will be open again, through the by-pass channel, 80 as soon as the head valve drops. Thus the parts are automatically restored to the positions shown in Figs. 1 and 2, and refilling of the displacement chamber occurs during 85 the cessation of the pumping force.

It will also be evident that by the employment of a common fluid pressure line, of 90 which the pipe 48 is one branch only, any number of wells may be equipped with my improved pumps, which will be automatically caused to function conjointly with or independently of any of the others, a feature of considerable importance when viewed from the aspect of my prefacing remarks 95 and the known needs of the industry.

While I have thus made a complete disclosure of a practical embodiment of my improvements, it may later be found to be desirable or expedient to make minor alterations or substitutions in the form and structural arrangement of elements, but without departing from the spirit of the invention; and it will be understood, therefore, that I do not limit myself necessarily to the exact 100 details shown and described, excepting as 105 they may come within the purview of the ensuing claims, when fairly interpreted in the light of the specification and understood equivalents.

What I do claim, as new and patentable, 110 is:—

1. An automatic pump of the character set forth, embodying a suitably walled displacement chamber, adapted for immersion as a bodily whole in a volume of liquid to be pumped, including a liquid inlet, a liquid outlet and a displacing pressure fluid inlet, the said liquid outlet being positioned toward one end of said chamber and the said pressure fluid inlet toward the other end 115 thereof; in combination with means automatically operable to open and close said pressure fluid inlet relatively to its source of supply; and means automatically operable to close said liquid outlet while opening said liquid inlet, when the displacing pressure fluid is cut off, and reversely to close said liquid inlet while opening said liquid outlet, when the displacing pressure fluid is cut 120 on, substantially as described.

2. An automatic pump of the character set forth, embodying a suitably walled displacement chamber, adapted for immersion as a bodily whole in a volume of liquid to be pumped, including a liquid inlet, a liquid outlet and a displacing pressure fluid inlet, the said liquid outlet being positioned at the lower zone of said chamber and the said pressure fluid inlet at the upper zone thereof; in combination with means automatically operable to open and close said pressure fluid inlet relatively to the source of its pressure fluid supply; and means operable by the incoming liquid to close said liquid outlet while opening said liquid inlet, when the displacing pressure fluid is cut off, and reversely operable by said pressure fluid to close said liquid inlet while opening said liquid outlet, when the displacing pressure fluid is cut on, substantially as described.
3. An automatic pump of the character set forth, embodying a suitably walled displacement chamber, adapted for immersion as a bodily whole in a volume of liquid to be pumped, including a liquid inlet, a liquid outlet and a displacing pressure fluid inlet, the said liquid outlet being positioned at the lower zone of said chamber and the said pressure fluid inlet at the upper zone thereof; in combination with means operable, by the rising level of inflowing liquid within said chamber, to open said pressure fluid inlet relatively to the source of its pressure fluid supply and reversely operable, by a back pressure of said pressure fluid itself, to cut off its supply source; and means automatically operable to close said liquid outlet while opening said liquid inlet, when the displacing pressure fluid is cut off, and reversely operable to close said liquid inlet while opening said liquid outlet, when the displacing pressure fluid is cut on, substantially as described.
4. An automatic pump of the character set forth, embodying a suitably walled displacement chamber, adapted for immersion as a bodily whole in a volume of liquid to be pumped, including a liquid inlet, a liquid outlet and a displacing pressure fluid inlet, the said liquid outlet being positioned toward the bottom of said chamber and the said pressure fluid inlet toward the top thereof; in combination with means operable, by the rising level of inflowing liquid within said chamber, to open said pressure fluid inlet relatively to the source of its pressure fluid supply and reversely operable, by a back pressure of said pressure fluid itself, to cut off its supply source; and means operable by the incoming liquid to close said liquid outlet while opening said liquid inlet, when the displacing pressure fluid is cut off, and reversely operable by said pressure fluid to close said liquid inlet while opening said liquid outlet, when the displacing pressure fluid is cut on, substantially as described.
5. An automatic pump of the character set forth, embodying a suitably walled displacement chamber, adapted for immersion as a bodily whole in a volume of liquid to be pumped, including a liquid inlet, a liquid outlet and a displacing pressure fluid inlet, the said outlet being positioned toward the lower end of said chamber and the said pressure fluid inlet toward the upper end thereof; in combination with means automatically operable to open and close said pressure fluid inlet relatively to the source of its pressure fluid supply; and a reciprocatingly incased foot valve operable by the incoming liquid to close said liquid outlet while opening said liquid inlet, when the displacing pressure fluid is cut off, and reversely operable by said pressure fluid to close said liquid inlet while opening said liquid outlet, when the displacing pressure fluid is cut on, the said foot valve being of unitary structure, having a depending stem slidingly associated with said liquid inlet and a stoppering plug cooperating with said liquid outlet, substantially as described.

6. An automatic pump of the character set forth, embodying a suitably walled displacement chamber, adapted for immersion as a bodily whole in a volume of liquid to be pumped, including a liquid inlet, a liquid outlet and a displacing pressure fluid inlet, the said liquid outlet being positioned toward the bottom of said chamber and the said pressure fluid inlet toward the top thereof; in combination with means operable, by the rising level of inflowing liquid within said chamber, to open said pressure fluid inlet relatively to the source of its pressure fluid supply and reversely operable, by a back pressure of said pressure fluid itself, to cut off its source of supply, the said means comprising a reciprocatingly incased head valve, suitably associated with portways and having a pressure face opposed to the upper interior space of said displacement chamber; and means automatically operable to close said liquid outlet while opening said liquid inlet, when the displacing pressure fluid is cut off, and reversely to close said liquid inlet while opening said liquid outlet, when the displacing pressure fluid is cut on, substantially as described.
7. An automatic pump of the character set forth, embodying a suitably walled displacement chamber, adapted for immersion as a bodily whole in a volume of liquid to be pumped, including a liquid inlet, a liquid outlet and a displacing pressure fluid inlet, the said liquid outlet being positioned toward the bottom of said chamber and the said pressure fluid inlet toward the top thereof; in combination with a head valve suitably associated with portways and venting means to cut on and cut off a supply source of pressure fluid through said pressure fluid in-

let, respectively, upon a predetermined rising and falling of the level of liquid within said displacement chamber, which head valve and venting means may be equipped with 5 suitable controlling floats as desired; and means automatically operable to close said liquid outlet while opening said liquid inlet,

when the displacing pressure fluid is cut off, and reversely to close said liquid inlet while opening said liquid outlet, when the displacing pressure fluid is cut on, substantially as described.

In testimony whereof, I affix my signature.
CHARLES B. PENDLETON.
